(57) **CLAIM**

The ornamental design for a marine compass, as shown and described.

DESCRIPTION

FIG. 1 is a perspective view taken from the top, front, and left side of the marine compass of the present invention in its closed configuration.

FIG. 2 is a front elevation view of the marine compass of FIG. 1.

FIG. 3 is a rear elevation view of the marine compass of FIG. 1.

FIG. 4 is a left side elevation view of the marine compass of FIG. 1, the opposite side being nearly a mirror image thereof.

FIG. 5 is a top plan view of the marine compass of FIG. 1.

FIG. 6 is a left side elevation view of the marine compass of FIG. 1 shown in its open configuration.

FIG. 7 is a perspective view of the marine compass of FIG. 1 shown in its open configuration.

FIG. 8 is a front elevation view of the marine compass of FIG. 1 shown in its open configuration; and,

FIG. 9 is a rear elevation view of the marine compass of FIG. 1 shown in its open configuration.
